ROOF RAIL

John Nugent Walters, New York, N. Y.; Rose P.
Walters administratrix of said John Nugent
Walters, deceased

Application September 26, 1946, Serial No. 699,361

1 Claim. (Cl. 108—26)

1 This invention relates to certain new and useful improvements in roof rails and aims to effect comprehensive savings in time and money by reducing the costs of labor and materials as well as to enhance, simplify and facilitate the joining of a water-tight permanently locked roof to the walls of trailer-vans, trucks, busses, buildings and/or the like.

My invention comprehends a contrivance of novel design which may be fabricated of metal or any other suitable materials of any thickness or gauge to any desired shape of any appropriate length and in any suitable manner consistent with the intent and purposes of what is claimed and in accordance with the spirit and scope thereof.

A principal feature of this invention, as will be readily perceived in the accompanying drawing, resides in a longitudinally formed preferably metal device provided with a series of perforations along the lower marginal edge thereof to permit the attachment and fastening of said device to the walls of a body under construction, the middle segment of said device being a slot-grooved flange into which the pre-formed bent edge of a suitable roofing material is received and locked therein by hammering down or pressing down the upstanding curved bead segment overhanging said groove into overlapping engagement with said roofing material thereby to achieve a water-tight permanently locked closure of roofing and sides.

It is the principal object of this invention to provide a roof rail of novel character which will unite roofing materials to the walls of structures of the type described herein more economically than any other contrivance of similar purpose heretofore existing, thereby to eliminate the laborious skills and costly operations entailed in measure spacing and marking out thousands of individual holes in the understructure of studs, struts and cross-beams of each unit to be roofed and the individual drilling of said thousands of holes; in addition thereto the same spacing and marking out of thousands of holes and the same drilling of thousands of individual holes must be duplicated in the roofing material itself; and again, thousands of holes must be similarly duplicated in a "finishing" strip; said "finishing" strip must then be "positioned" on top of the also "positioned" framework holes and the roofing holes for riveting down; plus, the individual insertion of thousands of rivets into the said holes, the individual "squeezing" or "heading" of the said thousands of rivets by two persons

opposing each other; requiring in addition, thousands of rivets to attach each roof to a body structure. Heretofore, all of these foregoing laborious and costly skills and actions have been necessary and required operations to achieve a water-tight and permanent closure in joining sheet roofing to the walls of trailer-van bodies, trucks, busses and similarly roofed structures. Thus, multiplying the foregoing "actions" by the thousands of times required for each unit under construction, it can be readily understood that my instant invention will very substantially reduce the cost of roofing, as well as greatly increase the production of said types of structures so sorely needed to advance the economic position of our nation.

With these and other objects and advantages in view, which will become apparent as the description proceeds, this invention resides in certain peculiar constructions, arrangements and combinations of the several segments thereof, as hereinafter described and claimed, by means of which to accomplish the purposes of said contrivance.

2 In the accompanying drawing, wherein similar reference characters designate corresponding parts throughout the several views, Figure 1 denotes a preferred embodiment of my invention constructed as disclosed herein. Figures 2 and 3 illustrate the several steps entailed in the application of my invention in accordance with the principles thereof.

This improved roof rail consists of a preferably metal longitudinal device as shown in Figure 1 wherein for descriptive and illustrative purposes the various segments of said device are identified by consecutive reference characters in which **1** indicates the lower portion thereof; **2** indicates perforations spaced at suitable longitudinal intervals thereof to facilitate attachment of the said device to body framework and walls by means of rivets or bolts inserted therein and fastened; the character **3** indicates a flange running the entire length of the mid-portion of said device at right angle to the lower portion thereof, providing means to rest said device upon the body framework and walls preparatory to attachment thereto; the character **4** indicates a slot grooved into and along the upper longitudinal surface of said flange by means of which the pre-formed bent edges of the sheet roofing are received and held preparatory to fixing therein; the character **5** indicates the upstanding curved bead segment overhanging said slot-grooved flange, likewise running the entire length of the

said device, by means of which, upon hammering down or pressing down the said bead into overlapping engagement therewith, the sheet roofing 6 (shown in Figure 2) is thereby interlocked to achieve a water-tight permanent joining of the roofing to the body under construction. As an alternative, without departing from the spirit and scope of my invention, said sheet roofing could be turned upside down and interlocked with a slot grooved into the bead portion instead of the flange of my device.

Figure 2, for illustrative purposes, denotes sheet roofing 6, the edges of which have been bent or creased as indicated by the character 7, being placed in hypothetical working position between two roof rails facing each other; as shown, the edges 7 are ready to be guided and lowered into the grooves 4 of the flanges 3, preparatory to attachment to the body under construction to achieve a water-tight permanent roof.

Figure 3 denotes a completed roof in the final stage; the edges 7 of sheet roofing 6 has been positioned into the grooves 4 of the flanges 3 and interlocked therein by hammering down or pressing down the upstanding curved bead segments 5 previously overhanging said grooved flanges 3 into overlapping engagement with the said roofing sheet 6, thereby accomplishing a water-tight permanent union of the roof with the walls of the body under construction. As here represented the roof rails are deemed to have been previously attached to the walls of the body under construction by riveting or other means, facilitated by the series of perforations 2 provided therefor in the lower marginal edges thereof.

From the foregoing description in connection with the accompanying drawing the construction, operation and application of my improved roof rail will be apparent; thus, the design, embodiments and fabrication of my invention having been completely described in the foregoing specifications, including the integral relationships of each component element to the whole thereof, as well as the applications of the said invention in accordance with the principles thereof,

anyone who is able to read should be able to manufacture and apply this invention to achieve the purposes for which it is intended.

It can be readily perceived that my instant invention may be constructed from stock materials and machined to incorporate the peculiarly designed elements, or the device could be cast, molded, extruded or otherwise fabricated if desired; therefore it is to be understood that the form of my invention constructed as described and disclosed herein is to be taken as the preferred embodiment of the same, and that many changes may be made to vary the structure, form, shape, size and arrangement of the elements and parts thereof without departing from the spirit of the invention or the scope of the claim.

Having thus described my invention, I hereby apply for the full protection of my interest and title in said invention and to the exclusive ownership of said rights therein under the security of United States Letters Patent.

I claim:

A metal edge moulding for roofs comprising a body portion having a depending flange thereon adapted to be attached to the edge wall of a roof, a flange extending at right angles to said first named flange at the upper inner edge thereof, the upper face of said second flange being grooved to receive a flexible sheet of roofing therein, and an upstanding curved bead portion overhanging said groove and of such length that it may be bent into overlapping engagement with a roofing sheet received therein.
